UNITED STATES PATENT OFFICE.

THOMAS C. MARSHALL, OF MOUNT SAVAGE, AND EDISON G. HULSE, OF CUMBERLAND, MARYLAND, ASSIGNORS TO KELLY-SPRINGFIELD TIRE COMPANY, OF CUMBERLAND, MARYLAND, A CORPORATION OF NEW JERSEY.

DESIGN FOR A VEHICLE TIRE.

Application filed May 5, 1923. Serial No. 6,073. Term of patent 14 years.

To all whom it may concern:

Be it known that we, THOMAS C. MARSHALL and EDISON G. HULSE, citizens of the United States, and residents, respectively, of Mount Savage, Allegany County, Maryland, and of Cumberland, Allegany County, Maryland, have jointly invented a new, original, and ornamental Design for a Vehicle Tire, of which the following is a specification, reference being had to the accompanying drawing, forming a part thereof.

Fig. 1 is a top view of the design.
Fig. 2 is a cross section through II-II of Fig. 1.

We claim:
The ornamental design for a vehicle tire, as shown.

THOMAS C. MARSHALL.
EDISON G. HULSE.
